UNITED STATES PATENT OFFICE.

OMAR L. BABCOCK AND CLINTON I. LENNEN, OF WINNEBAGO, NEBRASKA.

VEHICLE-JACK AND RIM-TOOL.

1,261,003.

Specification of Letters Patent. Patented Apr. 2, 1918.

Application filed March 6, 1917. Serial No. 152,555.

To all whom it may concern:

Be it known that we, OMAR L. BABCOCK and CLINTON I. LENNEN, citizens of the United States, and residents of Winnebago, in the county of Thurston and State of Nebraska, have invented certain new and useful Improvements in Vehicle-Jacks and Rim-Tools, of which the following is a specification.

The present invention relates to tools for use either as vehicle jacks or means for contracting demountable rims of vehicles.

The invention has for its primary object the production of an improved tool embodying certain novel features of construction and arrangement of parts which is adapted to be used either as a vehicle jack or as means for contracting and expanding demountable rims to permit demounting and mounting of tires therefrom and thereon.

Another object of the invention is the production of a combination vehicle jack and demountable rim tool adapted to be instantly adjusted and thoroughly efficient and dependable in operation, yet inexpensive in production.

Still another object of the invention is the production of a combination vehicle jack and demountable rim tool embodying certain novel features of construction and arrangements of parts whereby the tool may be instantly adjusted to approximately the length desired without resorting to the actuating mechanism.

With these and other objects in view, the invention consisting in the construction, combination and novel arrangement of parts will be fully understood from the following description reference being had to the accompanying drawings which form a part of this application and in which like characters of reference indicate corresponding parts throughout the several views, of which:

Figure 1 is a side elevation of a tool constructed in accordance with the invention;

Fig. 2 is a front elevation of the same a part being cut away;

Fig. 3 is a plan of the gear retaining member;

Fig. 4 is a transverse section of the jack screw pinion, the jack screw being shown in part; and

Fig. 5 is a fragmentary elevation of a demountable rim with the tool applied thereto.

Although we have illustrated and hereinafter described the preferred embodiment

of the invention we would not be understood as being limited to the specific structure chosen for illustration for various alterations and modifications in the details of construction and arrangement of parts may be made without departing from the spirit and scope of the invention as defined in the appended claims.

The invention contemplates, broadly, a jack including an extensible standard provided at its ends with means engageable with opposite sides of a tire rim to contract the same. Referring, now, to the illustrations, the embodiment chosen for illustration consists of a rectangular base, 6, formed integrally with a hollow upright, 7, internally threaded at its upper end as at 8, to receive a threaded hollow shaft, 9. The base and upright are braced on opposite sides by integral flanges or webs, 10. On opposite sides of the base and formed integrally therewith, are ears, 11, between which are pivoted hooks, 12.

The sides of the upright, 7, at right angles to the webs, 10, may be slotted as at 13, to reduce the amount of metal used and also afford access to the interior to free the threads from obstructions.

The shaft 9 is provided at its upper end with a sleeve, 14, which may be formed integrally with said shaft and is formed with a lateral stub shaft, 15, on which is freely mounted a toothed wheel, 16, formed with a bevel gear, 17, engaged by a beveled pinion, 18, supported by the sleeve, 14, and threaded on the jack shaft, 19, slidably inclosed by the shaft, 9. The shaft, 9, is slotted longitudinally as at 20, to receive studs or pins, 21, in the jack shaft which prevents relative rotation between the jack shaft and the shaft, 9.

Longitudinal movement of the pinion, 18, is prevented by means of a yoke, 22, formed integrally with opposite sides of the sleeve, 14, engageable with the upper end of the hub of the pinion and formed with an opening, 23, to freely inclose the jack shaft. The upper end of the jack shaft carries a suitable axle seat preferably consisting of a boss, 24, fixed on the jack shaft and provided with oppositely disposed lateral arms, 25, to which are pivoted hooks, 26, engageable with one side of a demountable rim.

The device is actuated by means of a lever, 27, pivoted on the stub shaft, 15, and provided with a relative short lateral arm,

- 28, to which is pivoted a pawl, 29, engageable with a toothed wheel, 16, and adapted to be thrown in opposite directions to drive the toothed wheel in opposite directions.
- 5 When the tool is applied as a jack, the upper hooks, 26, depend freely as shown and offer no obstruction to the operator or his work and the lower hooks are placed in the position shown in dotted lines in Fig. 1.
- 10 The shaft, 9, being threaded into the upright, 7, permits the jack to be readily extended or shortened to approximately the length desired, to lessen the labor of operating the lever, 27.
- 15 When applied to a demountable rim the device is attached as clearly presented in Fig. 5 with the hooks, 12 and 26, engaging the flanges of the rim at diametrically opposite points thereof. It will thus be seen that
- 20 the rim may be readily contracted and held in a contracted position while a tire casing is being removed or mounted and that the tool will also operate to expand the rim to force the adjoining ends into their interlocked positions.

Having thus described our invention what we claim as new and desire to secure by Letters Patent of the United States, is:—

1. In a vehicle jack and demountable rim
30 tool, a base, a hollow, internally threaded upright thereon, a hollow shaft threaded into said upright, said shaft being slotted

longitudinally, a threaded jack-shaft slidably inclosed by said hollow shaft, a pinion threaded on the jack-shaft and rotatably mounted on the hollow shaft, said jack-shaft having an axle supporting head and lateral studs engaged in the slots of the hollow shaft, ratchet mechanism operable to actuate the pinion, and hooks pivoted on opposite sides of the base and opposite sides of the head, said hooks being adapted to engage diametrically opposite sides of a demountable rim.

2. In a vehicle jack and demountable rim tool, a base, a hollow internally threaded upright thereon, a hollow shaft threaded therein and longitudinally slotted, an externally threaded jack-shaft slidably inclosed by the hollow shaft, a pinion threaded on 50 the jack-shaft and rotatably mounted on the hollow shaft, a yoke formed on the shaft to engage the upper side of the pinion, the jack-shaft being provided with an axle-supporting head, and hooks pivoted on opposite sides of the head, and opposite sides of the base, said hooks being engageable with diametrically opposite sides of a demountable rim.

In testimony whereof we have hereunto set our hands.

OMAR L. BABCOCK.
CLINTON I. LENNEN.
